UNITED STATES PATENT OFFICE

158,574

TELEPHONE NUMBER HOLDER

Harry B. Hampton, Altoona, Pa.

Application August 29, 1949, Serial No. 4,746

Term of patent 3½ years

(Cl. D74—1)

REFERENCES CITED

The following references are of record in the file of this patent:

UNITED STATES PATENTS

Number	Name	Date
D. 123,938	Sherman	Dec. 10, 1940
D. 141,727	Toussaint	June 26, 1945
D. 147,354	Sherr	Aug. 19, 1947

To all whom it may concern:

Be it known that I, Harry B. Hampton, a citizen of the United States, residing at Altoona, in the county of Blair and State of Pennsylvania, have invented a new, original, and ornamental Design for a Telephone Number Holder, of which the following is a specification, reference being had to the accompanying drawing, forming part thereof.

I claim:

The ornamental design for a telephone number holder, as shown.

HARRY B. HAMPTON.
